UNITED STATES PATENT OFFICE.

GUSTAV J. GEISSWEIN, OF CRANSTON, RHODE ISLAND, ASSIGNOR TO THE MOSLER SAFE COMPANY, OF NEW YORK, N. Y.

SAFE-LOCK.

SPECIFICATION forming part of Letters Patent No. 597,407, dated January 18, 1898.

Application filed July 6, 1897. Serial No. 643,516. (No model.)

To all whom it may concern.

Be it known that I, GUSTAV J. GEISSWEIN, residing at Cranston, county of Providence, State of Rhode Island, have invented certain new and useful Improvements in Safe-Locks; and I do hereby declare the following specification, taken in connection with the accompanying drawings, forming a part of the same, to be a full, clear, and exact description thereof.

10 The invention relates to safe-locks, and more especially to that class of locks in which the bolts are automatically cast on the closing of the door and automatically retracted at a predetermined time, said operations being effected by mechanism within the safe and inaccessible from the outside.

15 The object of the invention is to provide a simple and efficient mechanism for thus automatically casting and retracting the locking-bolts of a safe, and also to so construct and arrange said mechanism with relation to the bolts and the door of the safe that neither said mechanism nor the bolts will be affected by any attempt to force open the door, as by 20 the use of dynamite or other explosive.

A further object of the invention is to provide means for positively locking the bolts in their cast position, so that it will not be possible to retract said bolts against the tension of the spring which casts them.

To these ends the invention consists in the features and combinations hereinafter described, and set forth in the claims.

In the accompanying drawings, Figure 1 is a sectional view, partly in elevation, showing a bolt-operating mechanism embodying certain features of the present invention in their preferred form. Fig. 2 is a front elevation. Fig. 3 is a similar view showing the parts in a different position. Fig. 4 is a sectional view on line 4-4, Fig. 2. Fig. 5 is a view showing the bolt-operating mechanism applied to a screw-door safe. Fig. 6 is a sectional plan view of the parts shown in Fig. 5, and Fig. 7 is a view similar to Fig. 5 with the parts in a different position.

A block 3 is mounted to slide within the casing 1 and is provided with a rib 4, which projects into a slot 5, formed in the front of the casing. A spring 6 is interposed between the block 3 and a fixed abutment formed by

the end of the casing and tends to force the block 3 away from the end of the casing. The block 3 is recessed at 7 to receive the spring 6, and said spring is supported by a 55 stud 8, which is secured to the block 3 within the recess 7 and projects within a recess 9, formed in the end of casing 1. A bolt-operating slide 10 passes through the block 3, and a spring 11 is interposed between the end of 60 a recess 13 in block 3 and a shoulder 12, formed on the slide 10, said spring surrounding and being supported by said slide. The block 3 is moved forward to compress the spring 6 by means of a bell-crank lever 14, the short 65 arm 15 of which is provided with a stud 16, which projects within a slot 17, formed in the rib 4. The arm 15 of the bell-crank lever 14 is also provided with a lug or pin 18, which engages a slot 19, formed in an arm or lever 70 20, pivoted to the casing 1. The slot 19 has an offset 21 at its rear end, forming a shoulder for engaging the pin 18 when the block 3 is in its forward position. A pivoted detent 22, adapted to be rocked by a time mechanism, 75 engages the end of the arm 20 and holds the arm 20 in position to prevent the backward movement of the block 3. A collar 23 is secured to the slide 10 and is provided with a lug 24, arranged to be engaged by a detent 80 25, formed by a laterally-extending shoulder on an arm pivoted at 26 to the casing 1 and acted on by a spring 27. An arm 28 is secured to the pivot of the detent 25 outside the casing and serves to operate said detent 85 against the tension of the spring. A pin 29 limits the movement of the detent under the action of spring 27.

In practice the casing 1 will be arranged in suitable relation to the bolt mechanism of a 90 safe and the slide 10 connected with said bolt mechanism, so that the bolts will be retracted when the slide is retracted and said bolts will be cast when the slide is advanced. To set the mechanism so that the bolts will be automatically cast when the safe-door is closed and automatically retracted at a definite time, the block 3 is advanced by means of the lever 14 and is locked in position by means of arm 20 and detent 22. When said block 3 is 95 advanced, the spring 6 is compressed and is so held until the detent 22 is moved by the

time mechanism, to which it is attached. The advancing of the block 3 also compresses spring 11, since at this time the detent 25 engages the lug 24 and prevents the forward movement of slide 10. The time mechanism being set, the door of the safe is closed, and as it reaches its closed position the arm 28 is rocked by suitable devices and the spring 11 forces the slide 10 forward, thus casting the bolts of the safe, which remains locked until the time mechanism operates the detent 22, when the spring 6 acts to retract the bolts.

With the construction thus far described the bolts would be held cast by the action of spring 11 and it would be possible by drilling through the safe-casing and applying pressure to the bolts or bolt mechanism to force back the bolts against the tension of said spring, and it is therefore preferred to provide means for positively locking the slide 10 in its advanced position, which in the form shown is as follows: A detent in the form of a lever 30 is pivoted at 31 to the block 3 and has its free end arranged to engage a shoulder formed by the pin 32 on the slide 10 when said slide is in its forward position. The lever 30 is mounted in a recess 33 in the side of block 3 and is provided with a cam-surface 34, which rides over pin 35, secured to the casing 1, when the block 3 is forced back by spring 6, and thus raises the end of said lever above the pin 32. When the block 3 is moved forward, the end of lever 30 passes over pin 32, as shown in Fig. 1, and when the slide 10 casts the bolts said lever drops behind said pin, as shown in Fig. 2, and positively locks said slide in position. While it is preferred to use this form of locking mechanism for positively locking the slide in its forward position and to arrange the detent as shown, it will be understood that other forms of mechanism may be used or the mechanism be differently arranged without departing from the invention.

In safes as heretofore commonly constructed which are provided with automatic mechanism for casting and retracting the bolts it has been customary to mount the bolts and bolt mechanism upon the door, with the result that the bolts and bolt mechanism are subjected to any jar or shock to which the door is subjected, so that the bolt mechanism is liable to be injured or rendered defective as a result of an attempt to force open the door of the safe. It is accordingly preferred to provide the bolt-operating slide of the automatic bolt-operating mechanism with means for disconnecting the bolt mechanism and said slide when said slide is retracted, whereby the bolt mechanism may be mounted in the casing of the safe while the mechanism for automatically operating the bolts may be mounted upon or mounted to swing with the door, and this means preferably consists of a hook which is pivoted upon the end of the bolt-operating slide and is rocked into engagement with the bolt mechanism when the

slide is advanced and is rocked upon its pivot to disengage said mechanism when the slide is retracted.

As shown in the drawings, a hook 36 is pivoted at 37 to the end of slide 10 and is provided with two shoulders 38 and 39, which lie upon opposite sides of an abutment 40, formed on the end of the casing 1. When the slide 10 is retracted, the shoulder 38 engages abutment 40, rocking the hook 36 into the position shown in Fig. 1, and when said slide is advanced the shoulder 39 rides over the abutment 40, rocking said hook into the position shown in Fig. 2 and holding said hook in said position.

The mechanism above described may be used upon any form of safe and may be connected with the bolt mechanism of the safe in any suitable manner, and in Figs. 5, 6, and 7 is shown one manner of applying said mechanism to the screw-door safe illustrated in Patent No. 575,306, granted to M. Mosler January 12, 1897. As shown in said views, the door 41 of the safe is provided with a lug 42, arranged to be engaged by a bolt 43, pivoted to the casing 44 at 45. The bolt 43 is provided with a slot 46, engaged by a pin on the end of an arm 47, secured to a stud 48, mounted in a bracket 49, secured to the casing. An arm 50 is secured to the other end of stud 48 and is provided with a pin at its free end, arranged to be engaged by the hook 36, as shown in Fig. 7.

The casing 1 may be mounted upon the door, but is preferably secured upon the yoke 51, which supports the door of the safe, and a time mechanism 52 is connected to operate the detent 22 in a well-known manner. The arm 28 is arranged to be engaged by a lug 53, secured to the end of the screw 54, which is prolonged, so that it projects beyond the inner face of yoke 51. Instead of mounting the bolt mechanism upon the casing said mechanism may be mounted on the door or upon the yoke 51, or two bolt mechanisms may be used, as shown in the drawings. As shown, the second mechanism consists of a bolt 55, pivoted to the yoke 51 and operated by means of a lever 56, connected to the slide 10 by means of a link 57, which is pivoted to a projection 58 on the collar 23. The operation is as follows: The automatic mechanism is set, as shown in Figs. 1 and 5, and the door of the safe swung into register with the circular opening in the casing. The door is then turned upon its axis to close said door, and as it reaches its closed position the lug 53 strikes arm 28 and releases the slide 10, which is forced forward by the spring 11. This forward movement of slide 10 causes the hook 36 to engage the pin on arm 50 and to move said arm into the position shown in Fig. 7, thus operating the bolt 43 to engage lug 42 and lock the door in position. This movement of the slide also swings the bolt 55 above the lug 53, and said bolt also locks the door in position. The parts remain in this posi-

tion until the time mechanism operates the detent 22, when the slide 10 is retracted by the spring 6. The backward movement of the slide 10 moves the bolts 43 and 55 out of engagement with the lugs 42 and 53, thus unlocking the safe-door. After the bolt 43 has been operated the hook 36 is rocked to disengage the arm 50, so that the swinging movement of the door will not be interfered with.

While it is preferred to use two bolt mechanisms and to pivot the bolts and to arrange said bolts as shown, it will be understood that a single bolt mechanism may be used, or that sliding bolts may be used, if desired, and the arrangement of said bolts and the devices for connecting them with the automatic mechanism varied without departing from the invention.

20 What I claim as my invention, and desire to secure by Letters Patent, is—

1. The combination with a bolt-operating slide, of automatic means for operating said slide to cast and retract the bolts, and means for positively locking said slide in its advanced position, substantially as described.

2. The combination with a bolt-operating slide, of casting and retracting springs for operating said slide, and a detent for positively locking said slide in its advanced position, substantially as described.

3. The combination with a bolt-operating slide, casting and retracting springs for operating said slide, a detent for restraining the casting-spring, a detent for restraining the retracting-spring and means independent of the latter detent for positively locking said slide in position, substantially as described.

4. The combination with a bolt-operating slide, a sliding block, a spring interposed between said slide and block, a spring interposed between said block and a fixed abutment, means for energizing said springs, means for restraining and releasing said springs, and means for positively locking said slide in its advanced position, substantially as described.

5. The combination with a bolt-operating slide, of a sliding block, a spring interposed between said slide and block, a spring interposed between said block and fixed abutment, means for energizing said springs, means for restraining and releasing said springs, a detent carried by said block, and arranged to engage and lock said slide, substantially as described.

6. The combination with a bolt-operating slide, a sliding block, a spring interposed between said slide and block, a spring interposed between said block and a fixed abutment, means for energizing said springs,

means for restraining and releasing said springs, and a detent operated by the movement of said block for engaging and locking said slide, substantially as described. 65

7. The combination with a casing and a bolt-operating slide within said casing, of springs for operating said slide, a sliding block for energizing said springs, a slot in said block, a lever outside the casing provided with a pin engaging said slot for operating said block, substantially as described. 70

8. The combination with a bolt-operating slide, springs for operating said slide, a block for energizing said springs, a slot in said block, a lever provided with a pin engaging said slot, a lug on said lever, an arm provided with a shoulder for engaging said lug, and a detent for engaging said arm, substantially as described. 75 80

9. In a safe, the combination with a locking-bolt, of a spring-operated slide for operating said bolt, and means for disconnecting said slide and bolt when said slide is retracted, substantially as described. 85

10. The combination with a bolt-operating slide, of means for reciprocating the same, a hook pivoted to said slide and means for rocking said hook upon its pivot as said slide is reciprocated, substantially as described. 90

11. The combination with a bolt-operating slide, of springs for advancing and retracting said slide, detents for restraining said springs, a hook pivoted to said slide, and means for rocking said hook on its pivot, substantially as described. 95

12. The combination with a bolt-operating slide, of springs for advancing and retracting said slide, detents for restraining said springs, a hook pivoted to said slide and provided with two shoulders, and a fixed abutment for engaging said shoulders, substantially as described. 100

13. In a safe the combination with a casing having a circular door-opening, of a rotary door adapted to close said opening, a locking-bolt on the casing, and mechanism for automatically operating said bolt mounted to swing with said door, substantially as described. 105 110

14. In a safe, the combination with a casing having a circular door-opening, of a rotary door adapted to close said opening, a pivoted yoke on which said door is supported, one or more bolts for engaging said door, and mechanism mounted on said yoke for operating said bolts, substantially as described. 115
